COMBINED WINDOW SHADE, CURTAIN, AND DRAPERY SUPPORT

Filed Dec. 30, 1927

UNITED STATES PATENT OFFICE

WILLIAM BUSHEY AND ERNEST H. BUSHEY, OF PLATTSBURG, NEW YORK

COMBINED WINDOW SHADE, CURTAIN, AND DRAPERY SUPPORT

Application filed December 30, 1927. Serial No. 243,665.

The present invention is directed to improvements in combined window shade, curtain and drapery supports.

The primary object of the invention is to provide a device of this character so constructed that it can be attached to window frames which vary in width.

Another object of the invention is to provide a device of this kind which is simple in construction, neat in appearance and one which will effectively support the shade roller, curtain, and draperies in proper relationship upon a window frame.

Another object of the invention is to provide a device of this kind which can be conveniently attached to a window frame, and one which can be manufactured at a very small cost.

With these and other objects in view, this invention resides in the novel features of construction, formation, combination and arrangement of parts to be hereinafter more fully described, claimed and illustrated in the accompanying drawing, in which,—

25 Figure 1 is a perspective view of the device showing it attached to a window frame.

Figure 2 is a transverse sectional view.

Figure 3 is a detail perspective view of one end of the bar.

30 In constructing the device, a pair of sheet metal brackets 1 are employed which have flanges 2 serving to receive securing devices to attach the brackets to the window frame. These brackets, as customary, serve to support the usually constructed spring shade roller and each is provided upon its upper edge with a seat 3 for receiving the tubular supporting rod 4, which consists of telescopically connected sections 5, each section having a groove 6 therein to engage the seat to prevent endwise movement of said rod.

35 Used in connection with the rod 4 are outer plates 7 and an intermediate plate 8, said plates being provided, respectively, with openings 9 in which the rod 4 is engaged.

The plates have their lower ends provided with a pair of vertically disposed laterally spaced slots 10 and in which are engaged the paired curtain supporting bars 11 and drapery supporting bars 11', the outer ends of

which are provided with flanges 12 which serve to prevent disengagement of the bars from the slots of the plates 7 when said plates are slid outwardly upon the rod 4. The outer ends of the bars are provided with notches 13 which engage the lower walls of the slots 10 so that when the plates 7 are slid inwardly the bars will be moved likewise. The inner ends of the bars are arranged in overlapped relation and engaged in the slots 10 of the intermediate or middle plate 8. It will be observed that the bars 11 and 11' are arranged in spaced relation in order that the curtain can be fastened to the former and draperies secured to the latter, and upon opposite sides of the intermediate plate 8.

From the foregoing description, it will be seen that a device has been provided constructed and arranged in such manner that a shade roller, curtain and draperies can be supported in proper relationship and that the device can be conveniently adjusted to fit window frames of various widths.

Having thus described the invention, we claim:

1. A device of the class described, comprising a pair of spaced brackets, a rod supported by the brackets, outer plates slidably adjustable on the rod, an intermediate plate supported by the rod, paired bars having their outer ends engaged in the outer plates and their inner ends supported in overlapped relation in the intermediate plate, said bars being disposed in spaced parallel relation.

2. A device of the class described, including a rod, outer plates slidably adjustable on the rod, an intermediate plate supported by the rod, said plates having spaced slots therein, paired bars having their outer ends interlocked in the slots of the outer plates, and their inner ends arranged in sliding overlapped relation in the slots of the intermediate plate, said bars being arranged in spaced parallel relation throughout their length.

In testimony whereof we affix our signatures.

WILLIAM BUSHEY. [L. S.]
ERNEST H. BUSHEY. [L. S.]
